CURVED TRACK SECTION FOR MINIATURE TOY VEHICLES

William R. Baynes and Harvey W. La Branche, Palos
Verdes Peninsula, and George Soulakis, Los Angeles,
Calif., assignors to Mattel, Inc., Hawthorne, Calif.

Filed Feb. 2, 1970, Ser. No. 21,178

Term of patent 14 years

Int. Cl. D21—02

U.S. Cl. D34—15

Fig. 1

Fig. 7

Fig. 8

Fig. 9

FIG. 4

FIG. 3

FIG. 1 is a top plan view of a curved track section for miniature toy vehicles showing our new design;

FIG. 2 is a front view of same;

FIG. 3 is a bottom view of same;

FIG. 4 is an exploded top plan view of FIG. 1;

FIG. 5 is an elevational view of same taken at lines 5—5 of FIG. 4;

FIG. 6 is an elevational view of same taken at lines 6—6 of FIG. 4;

FIG. 7 is a sectional view of same taken at approximately lines 7—7 of FIG. 4;

FIG. 8 is an elevational view of same taken at lines 8—8 of FIG. 4; and

FIG. 9 is an elevational view of same taken at lines 9—9 of FIG. 4.

We claim:

The ornamental design for curved track section for miniature toy vehicles, as shown and described.
